United States Patent Office

Des. 216,329
Patented Dec. 16, 1969

216,329

DRAWING INSTRUMENT

John W. Waterloo, Sr., 217 Richard Road,
Chester, Pa. 19014

Filed Apr. 16, 1969, Ser. No. 16,758

Term of patent 14 years

Int. Cl. D10—08

U.S. Cl. D52—6

Fig. 1

Fig. 2

Fig. 3

Fig. 4

FIGURE 1 is a top plan view of a drawing instrument showing my new design the markings appearing through the transparent body.

FIGURE 2 is a side view of my new design, both side views being identical.

FIGURE 3 is an end view showing my new design, both end views being identical.

FIGURE 4 is a fragmentary cross-sectional view showing a typical edge region of the drawing instrument of my new design.

I claim:

The ornamental design for a drawing instrument, as shown.
